FIG. 3

FIG. 4

INVENTOR

R. H. LANSING
Joseph J. O'Brien
ATTORNEY

UNITED STATES PATENT OFFICE.

RICHARD H. LANSING, OF CHICOOPEE FALLS, MASSACHUSETTS.

FABRIC-WORKING MECHANISM.

1,425,987.

Specification of Letters Patent. Patented Aug. 15, 1922.

Application filed April 6, 1921. Serial No. 459,184.

To all whom it may concern:

Be it known that RICHARD H. LANSING, a citizen of the United States of America, residing at Chicopee Falls, in the county of 5 Hampden and State of Massachusetts, has invented certain new and useful Improvements in Fabric-Working Mechanism, of which the following is a specification.

This invention relates to improvements in 10 a flipper mechanism for bias cutters of the type known as the Bolton and its leading object is to provide a rotary flipper bar arranged to cooperate with a grab bar and means for imparting intermittent rotative 15 movement to the flipper bar controlled by said grab bar.

With the above and other objects in view this invention relates to certain new and useful constructions, combinations and arrangements of parts, clearly described in 20 the following specification, and fully illustrated in the accompanying drawings, in which:

Figure 1 is a side elevation.

Figure 2 is a transverse sectional view.

Figure 3 is a transverse sectional view taken on an enlarged scale, of Figure 1.

Figure 4 is a transverse sectional view taken on Figure 1, on an enlarged scale.

Referring to the accompanying drawings 30 5 designates an I beam frame which provides parallel horizontal guide bars 6 and 7 between which a grab bar 8 slides. This grab bar is formed with a recess 8^a which 35 confronts the members 9 and 10 forming part of the well known Spadone construction.

On the frame 5 the bearings 11 and 12 are mounted so as to depend from the guide 40 bar 7 and on these bearings 11 and 12 the flipper bar 13 is journaled upon the shafts 14 and 15 supported by the bearings 11 and 12. The flipper bar 13 is provided with oppositely facing longitudinal grooves 16 45 and 17 located on opposite sides of said bar. In each of the grooves a flexible flipper member 18 is secured so that the outer longitudinal edge portion will present a yielding fabric engaging wing. The flipper bar 50 13 is pivoted so that the fabric engaging wings of the strips 18 will swing into the vertical plane described by the gap between the grab bar 8 and the adjacent faces of the members 9 and 10. The strips 18 each include a retaining head 18^a arranged to slide in pockets formed by the grooves 16 and 17

against the tension of coil springs 19. The coil springs 19 engage socket 20 provided in said flipper bar and can be removed or replaced by means of caps 21 threaded on the sockets 20. The flipper strips 18 can be removed by means of retaining plates 22 secured in place by screws 23. The springs 19 provide means for maintaining the members 18 under tension and permit 65 of a yielding movement of said members 18.

On the shaft 14 a ratchet wheel 25 is mounted which is provided with four teeth 26 radially spaced an equal distance from each other. On the shaft 14 an arm 27 is 70 mounted and this arm carries a pawl 28 pivoted thereto to engage the teeth 26 in succession. An operating rod or link 29 is also pivotally connected with the arm 27 and this link is pivotally secured to a lever 75 30 which is pivoted at 31 to the bracket 32. The pivot 33 which connects the arm or link 29 to the lever 30 also connects the link 33' to said lever and this link has a pawl 34 pivoted thereto by the pin 35 so 80 that said pawl will engage the teeth 26 in succession, the two pawls being supported so that two of said teeth are simultaneously engaged. The pivot 35 is connected to the shaft 14 by an arm similar to the arm 85 27 so that a pawl 35 will be maintained in the same relation to the ratchet 25 that the pawl 28 is. An operating link 36 is pivoted at one end to the lever 30 and at the other end to the bracket 37 which is secured to 90 the member 38 arranged to slide on the base 39.

With each movement of the member 38 the lever or arm 30 will be swung toward the shaft 40 and the ratchet wheel 25 advanced one-half of a turn and this action will swing the members 18 carried by the flipper bar in an arc against the fabric.

Having described my invention I claim:

1. The combination with a grab bar, a spring pressed element being supported to rotate close to one edge of the grab bar with a fabric working machine, of flipper mechanism consisting of a rotative bar and a spring pressed element carried by said bar. 105

2. The combination with a grab bar, a spring pressed element being supported to rotate close to one edge of the grab bar with a fabric working machine, of flipper mechanism consisting of a rotative bar and independent spring pressed members carried by the bar. 110

3. A combination with a grab bar of a fabric working machine, of flipper mechanism consisting of a rotative bar, yielding members on said bar, and means for imparting a step-by-step rotative movement to the bar, the bar being supported to rotate close to one edge of the grab bar.
4. A flipper mechanism consisting of a rotative bar, means slidably mounted on said bar, springs engaging said means, said means projecting from said bar on opposite sides thereof, and means for imparting a step-by-step rotative movement to the bar.
5. A flipper mechanism consisting of a rotative bar, spring pressed means carried

thereby, a ratchet, and pawl mechanism engaging the ratchet for imparting a step-by-step rotative movement to the bar.

6. A flipper mechanism consisting of a rotative bar, spring pressed elements carried by said bar and projecting on the opposite sides thereof, a pawl mechanism, means for imparting movement to the pawl mechanism, and a ratchet associated with the bar and acted on by the pawl mechanism, whereby said bar will be given a step-by-step rotative movement when said pawl mechanism is actuated.

Signed by me at Chicopee Falls.
RICHARD H. LANSING.
